UNITED STATES PATENT OFFICE.

WILLIAM F. LETSCH, OF CARBON CLIFF, ILLINOIS.

POTATO-DIGGER.

SPECIFICATION forming part of Letters Patent No. 320,369, dated June 16, 1885.

Application filed March 27, 1885. (No model.)

To all whom it may concern:

Be it known that I, WILLIAM F. LETSCH, a citizen of the United States, and a resident of Carbon Cliff, in the county of Rock Island 5 and State of Illinois, have invented certain new and useful Improvements in Potato Diggers; and I do hereby declare that the following is a full, clear, and exact description of the invention, which will enable others skilled in 10 the art to which it appertains to make and use the same, reference being had to the accompanying drawings, which form a part of this specification, and in which—

Figure 1 is a perspective view of my improved potato-digger. Fig. 2 is a longitudinal vertical sectional view of the same. Fig. 3 is a rear elevation. Fig. 4 is a top view, and Fig. 5 is a detail view, in perspective and on a larger scale, of a portion of the operating mechanism of my improved potato-digger. Fig. 6 is a different view of the same with a part broken away.

The same letters refer to the same parts in all the figures.

This invention relates to potato-diggers; and it has for its object to produce a device of this class which shall possess superior advantages in point of simplicity, durability, and general efficiency.

With these ends in view the invention consists in the improved construction and arrangement of parts, which will be hereinafter fully described, and particularly pointed out in the claims.

In the drawings hereto annexed, A designates the frame of the machine, which consists of a transverse bar, B, the ends of which are provided with downwardly-extending lugs C C, forming boxes or bearings for the axle D. The ends of the frame-bar are also provided 40 with rearwardly-extending brackets E E.

F is the tongue, which is secured to the frame by means of the curved supports G, having holes H, through which passes the axle D.

I is a lever or handle secured to one side of the tongue, the lower end of which is connected with the frame-beam B by means of the bent arm J.

L is a segmental rack provided with notches, 50 in which a catch, K, engages.

The ends of the axle D are provided with transporting-wheels M M, mounted loosely

thereon, and provided on their inner sides with spring-clutches of suitable construction, whereby they may be connected with the spur-wheels N N, which are fixed upon the axle. 55 By this construction provision is made for conveniently turning the machine, while, when the machine moves forwardly over the field, the spur-wheels N will revolve with the transporting-wheels, thereby conveying motion to the operating parts, as will be presently more fully described. The rear ends of the brackets E E are provided with bearings for a pair of short shafts, O O, the ends of which carry 60 pinions P P, meshing with and operated by the spur-wheels N N. At F' F', upon the inner sides of the brackets E E, is pivoted a suitably-constructed scoop, P', having a forwardly-extending bail, Q, to which the draft 70 may be attached, and provided at its rear corners with rearwardly-extending brackets R R, each of which has two downwardly-extending arms, S S. By means of the lever I the beam B is drawn forward and the brackets E E 75 correspondingly elevated, and with them the scoop P', thus affording a simple and efficient means for adjusting the machine to different depths.

The rear ends of the brackets R R are provided with laterally-extending frames T T, affording bearings for short transverse shafts U U, the outer ends of which are provided with cranks V V, connected by pivoted rods or pitmen W W, with wrist-pins X X upon 80 the outer sides of the pinions P P, from which an oscillating or rocking motion is thus conveyed to the shafts U U.

Y Y are a pair of bails or suitably-constructed frames, the legs Z Z at the ends of 90 which are fitted to slide vertically upon the outer sides of the arms S S, extending downwardly from the brackets R R of the scoop. The ends of the legs Z Z are provided with diagonal cross-bars A', to the ends of which 95 are pivoted grooved rollers B', fitting against the edges of the arms S, thus retaining the bails or frames Y Y in position and guiding them in their vertically-reciprocating motion upon the arms S S. The frames Y Y are provided with rearwardly-extending fingers C', raised slightly above said frames by means of short-arms D', and arranged alternately upon the two frames, as shown. The said fingers 100

are flat on top, as shown, and they serve, when the frames upon which they are mounted are reciprocated alternately in opposite directions, to screen the potatoes and separate them from the dirt.

It will be observed that the guide-pulleys B' of each carrying-frame being located at different levels, or in different horizontal planes, there is no obstacle to the elevation of the rear ends of the screening-fingers, which will, in fact, be vibrated freely by the jolting of the machine in passing over the ground, and they will the more readily pass over any obstruction that may be encountered.

15 A seat, E', for the driver is to be suitably mounted upon the tongue, near the rear end of the latter.

From the foregoing description, taken in connection with the drawings hereto annexed, 20 the operation and advantages of this invention will be readily understood.

By means of the adjusting-lever I the scoop, with its attachments, may be set so as to be simply carried by the machine, or so as to 25 work at any desired depth. When the scoop is set to work, the dirt and potatoes will be together raised or elevated by it, and slide over it, finally dropping upon the fingers of the vertically-reciprocating frames Y Y, whereby 30 they are screened, the dirt falling through between the fingers and the potatoes rolling off at the rear ends of the same, being thus deposited upon the surface of the ground in a row, so that they may be easily gathered.

35 The construction of the machine is simple and inexpensive, and it is exceedingly durable, and not liable to get out of order.

Having thus described my invention, I claim and desire to secure by Letters Patent of the 40 United States—

1. In a potato-digger, the combination of a transverse frame-beam having rearwardly-extending brackets and downwardly-extending journal-boxes, the revolving axle mounted in 45 the latter, means for adjusting the frame and its attachments upon or with relation to the axle, a scoop mounted pivotally between the

rearwardly-extending brackets of the frame-beam, and having rearward-extending brackets at its rear corners, provided with downwardly-extending arms, vertically-reciprocating frames mounted to slide upon the said arms and equipped with rearwardly-extending fingers, and suitable operating mechanism, substantially as and for the purpose herein set forth.

2. In a potato-digger, the combination, with the herein-described adjustable frame, of the pivoted scoop having rearwardly-extending brackets provided with downwardly-extending arms, bails or frames provided at their ends with diagonal cross-pieces, having grooved rollers arranged at different levels, and engaging the edges of said arms, fingers mounted upon and extending rearwardly from 65 said bails or frames, and mechanism for reciprocating the latter vertically, substantially as and for the purpose set forth.

3. The combination of the adjustable frame having rearwardly-extending brackets, pinions journaled to the latter, and arranged to be operated by suitable spur-wheels, the pivoted scoop having rearwardly-extending brackets, rock-shafts journaled in the latter, and having cranks connected by pivoted rods 70 or pitmen, with wrist-pins upon the pinions, bails or frames having rearwardly-extending fingers, and provided with inclined cross-pieces, having grooved-rollers located in different horizontal planes, and bearing upon 75 the edges of arms extending downwardly from the brackets of the scoop, and pivoted rods or pitmen connecting the said bails or frames with the ends of arms or cross-bars mounted upon the rock-shafts, substantially as and for 80 the purposes herein set forth.

In testimony that I claim the foregoing as my own I have hereunto affixed my signature in presence of two witnesses.

WILLIAM F. LETSCH.
